US00D883805S

(12) **United States Design Patent** (10) Patent No.: **US D883,805 S**
(45) Date of Patent: **** May 12, 2020**

(54) **PACKAGING TRAY**

(71) Applicant: **MEATY MEATS INC.**, Mississauga (CA)

(72) Inventors: **Peter Abdnour**, Rockland (CA); **Gowkarran Mangru**, Rockland (CA)

(73) Assignee: **MEATY MEATS INC.**, Mississauga, ON (CA)

(**) Term: **15 Years**

(21) Appl. No.: **29/668,935**

(22) Filed: **Nov. 2, 2018**

(30) **Foreign Application Priority Data**

Jun. 29, 2018 (CA) 182195

(51) LOC (12) Cl. **09-03**

(52) U.S. Cl.

USPC **D9/756; D9/761**

CLAIM

The ornamental design for a packaging tray, as shown and described.

DESCRIPTION

FIG. 1 is a isometric view of a packaging tray;

FIG. 2 is a top view thereof;

FIG. 3 is a bottom view thereof;

FIG. 4 is a side view thereof;

FIG. 5 is an opposite side view thereof;

FIG. 6 is an end view thereof; and,

FIG. 7 is an opposite end view thereof.

1 Claim, 3 Drawing Sheets
